UNITED STATES PATENT OFFICE.

THOMAS WINSTANLEY, OF BLACKBURN, ENGLAND, ASSIGNOR TO BRITISH HUMIDIFIER COMPANY, LIMITED, OF BLACKBURN, ENGLAND.

HUMIDIFIER OR SPRAY-PRODUCER.

981,149.

Specification of Letters Patent. Patented Jan. 10, 1911.

Application filed June 9, 1910. Serial No. 565,984.

To all whom it may concern:

Be it known that I, THOMAS WINSTANLEY, residing at 8 Livingstone road, Blackburn, in the county of Lancaster, England, have 5 invented certain new and useful Improvements in Humidifiers or Spray-Producers; and I do hereby declare the following to be a full, clear, and exact description of the invention, such as will enable others skilled 10 in the art to which it appertains to make and use the same.

This invention relates to improvements in humidifiers or spray producers or apparatus for moistening the warp threads in looms 15 when weaving. In order to produce the desired spray by the use of a brush revolving in a trough of water in the manner now practised it is essential that the revolving brush should be rotated at a comparatively 20 high speed and when this is done there is a tendency to throw the water out in too large a quantity or in drops instead of spray.

The object of the present invention is to overcome this defect and produce a very fine 25 equal spray when the brush is rotated at a low speed driven by gear or ratchet and pawl from the crank shaft or other going part of the loom. Provision is also made 30 whereby the spray can be localized and directed or delivered in any desired direction.

The invention consists in the use in combination with a rotary brush of a stationary brush with which the rotary brush is in contact and by which the water taken up is dispersed in a fine spray.

Referring to the drawings which form a part of this specification—Figure 1 is a front elevation of the improved humidifier. Fig. 2 is a plan view of Fig. 1. Fig. 3 is 40 an end elevation of the improved humidifier a portion of one of the gear wheels being broken away. Fig. 4 is a cross sectional view of the humidifier.

According to this invention a stationary 45 and adjustable brush 1 is arranged on the inside upper part of the water trough 2. The revolving brush 3 rotates in contact with the stationary brush 1 and the water taken up by the revolving brush 3 is owing 50 to the joint action of the revolving brush 3 on and with the stationary brush 1 thrown in the form of a fine spray through the

gauze or perforated cover 4 of the opening in the trough 2. The combination of a revolving brush 3 with a stationary brush 1 55 produces the required fine spray and the revolving brush 3 can be driven at a low speed by means of gear or ratchet wheel and pawl from any going part or shaft of the loom. The revoluble brush may however be driven 60 in any other approved manner. Heretofore it has only been possible to deliver the spray in one direction but this invention provides means whereby the spray can be delivered in any desired direction and localized on 65 any required point. This is accomplished by arranging the humidifier apparatus so that it can swivel on its trunnions 5—5 in its supporting brackets or pedestals 6—6 and be fixed or locked after setting to the desired 70 position or angle by tightening the screws 7.

The bristles of the stationary brush project from a bar 10 which is secured to the top edge of the trough so that the bristles 75 project within the trough, and so that the brush 1 is moved with the trough when the trough is adjusted pivotally on its trunnions.

A convenient method of driving the revolving brush 3 is by mounting on the shaft or axis 8 of same a toothed wheel 9 meshing with a like wheel 10 on the stud 11 fixed in the bracket 12. On the stud 11 is also mounted a rocking lever 13 on the cranked 85 end 14 of which is mounted the pawl 15 which at each downward stroke of the lever 13 operates the ratchet wheel 16 fixed on the boss of the wheel 10 so that the latter is rotated and drives the wheel 9 and brush 3. 90 The lever 13 may be rocked or actuated from the crank shaft of the loom or in other desired manner from any desirable source.

The trough or humidifier is disposed or fixed to the loom adjacent to the warp 95 threads so that the spray is localized on the warps and the atmosphere generally remains normal.

Having now described my invention what I claim as new and desire to secure by Letters Patent is:—

In a humidifier, the combination, with a trough for holding water having a delivery opening, of a circular brush journaled in-

side the trough, means for adjusting the
trough pivotally on the axis of the said
brush, and a stationary brush secured to the
trough at one side of its delivery opening
5 and bearing against the circular brush, said
stationary brush being movable with the
trough when the trough is adjusted.

In testimony whereof I affix my signature,
in presence of two witnesses.

THOMAS WINSTANLEY.
